US00D513461S

(12) **United States Design Patent** (10) Patent No.: **US D513,461 S**
Kwok (45) Date of Patent: **** Jan. 10, 2006**

(54) **MODULE FOR STORAGE RACK FOR COMPACT DISCS, CASSETTES, AND THE LIKE**

(75) Inventor: **Tat Cheong Kwok**, Hong Kong (CN)

(73) Assignee: **Kwok's Brother Manufacturing Limited**, Hong Kong (HK)

(**) Term: **14 Years**

(21) Appl. No.: **29/203,271**

(22) Filed: **Apr. 13, 2004**

(51) LOC (8) Cl. **06-04**

(52) U.S. Cl. **D6/630**

(58) Field of Search D6/629-632; D21/500, D21/501; 211/40, 41.18, 87.01, 90, 134, 186-189; 108/91, 92, 99, 115; 206/387.15, 307.1; 312/9.9, 9.64, 9.48, 9.53

(57) **CLAIM**

The ornamental design for a module for storage rack for compact discs, cassettes, and the like, as shown and described.

DESCRIPTION

FIG. 1 is a front perspective view of the claimed design viewed from the top left;

FIG. 2 is a rear perspective view of the claimed design viewed from the bottom right;

FIG. 3 is a front elevational view of the claimed design;

FIG. 4 is a rear elevational view of the claimed design;

FIG. 5 is a left side elevational view of the claimed design;

FIG. 6 is a right side elevational view of the claimed design;

FIG. 7 is a top plan view of the claimed design;

FIG. 8 is a bottom plan view of the claimed design;

FIG. 9 is a front perspective view of a second embodiment of the claimed design viewed from above left, illustrating three articles in a first arrangement;

FIG. 10 is a rear perspective view of the design of FIG. 9;

FIG. 11 is a front perspective view of a third embodiment of the claimed design viewed from above left, illustrating five articles in a second arrangement; and,

FIG. 12 is a rear perspective view of the design of FIG. 11.
